UNITED STATES PATENT OFFICE.

CHARLES WILLES, OF EAST AUBURN, CALIFORNIA, ASSIGNOR OF ONE-HALF TO C. E. COLE, OF EAST AUBURN, CALIFORNIA.

WASHING-MACHINE.

1,026,540.

Specification of Letters Patent.

Patented May 14, 1912.

Application filed May 21, 1911. Serial No. 630,341.

To all whom it may concern:

Be it known that I, CHARLES WILLES, a citizen of the United States, residing at East Auburn, in the county of Placer and State of California, have invented new and useful Improvements in Washing-Machines, of which the following is a specification.

The invention relates to washing machines, and has for its primary object to provide a machine of this character in which soiled clothes, when placed therein, will be thoroughly cleansed through the medium of reversely movable agitating mechanism, the same being actuated by means of a rotary driving element.

Another object of the invention is the provision of a washing machine in which continuous reversely reciprocating movement will be imparted to agitating mechanism, interiorly of the body of the machine, the agitating mechanism being operated by means of a rotary driving element, thereby affording the positive driving of the said agitating mechanism, so as to effect a constant agitation of the contents of the body for the thorough cleaning of clothes held within said body, when the machine is active.

A further object of the invention is the provision of a washing machine which is simple in construction, easy, smooth and efficient in operation, and inexpensive in manufacture.

With these and other objects in view, the invention consists in the construction, combination and arrangement of parts, as will be hereinafter more fully described, illustrated in the accompanying drawings, and pointed out in the claim hereunto appended.

In the drawings: Figure 1 is a side elevation of a washing machine constructed in accordance with the invention. Fig. 2 is an end elevation thereof. Fig. 3 is a vertical longitudinal sectional view through the same. Fig. 4 is a transverse sectional view. Fig. 5 is a fragmentary enlarged vertical sectional view, showing the crank shaft for reversely driving the agitator head or slatted drum interiorly of the washing machine. Fig. 6 is an enlarged fragmentary view of the connections between the crank shaft and the oscillatory arms for driving the agitator head and drum.

Similar reference characters indicate cor-

responding parts throughout the several views of the drawings.

Referring to the drawings by numerals, the washing machine comprises a body or casing 5, the side and end walls of which are preferably constructed from wood, although the same may be made from any other suitable material, and its bottom 6 is preferably constructed from galvanized iron, bent into semi-cylindrical shape although the said bottom 6 may be made from any other suitable material. The body or casing 5 is supported by downwardly diverging legs 7, as usual, thereby elevating the body from the flooring or foundation. The body, at its top, is closed by a hinged cover or lid 8, which, when opened, will permit the introduction of water or washing compound thereinto, as may be desired.

Arranged within the body or casing 5 is a semi-rotary drum 9, the cylindrical side wall of which is formed of spaced longitudinal slats 10, suitably fixed in the circular ends or heads 11 thereof, the drum being provided with a hinged door 12 coextensive with the length thereof, so that clothes may be introduced into and removed from the drum at will, the door being held in closed position by any suitable fastening device.

Fixed to the outer faces centrally of the heads or ends 11 of the drum 9, are bearing hubs 13, the same alining with similar bearing hubs 14 fixed exteriorly to the end walls of the body or casing 5, centrally thereof, and in these alining hubs are journaled stud shafts 14 and 15, respectively, the inner ends of which project into the drum 9 and have fixed thereto circular-shaped rubbing heads 16 carrying dasher arms 17 which are adapted to engage clothes disposed within the drum 9 on the reverse semi-rotation of the heads and drum, so as to twist or rinse such clothes for the cleaning thereof, the rubbing heads and drum 16 and 9, respectively, being operated as presently described.

The drum 9 has fitted in one head or end 11 thereof an outwardly extending sleeve 18, the latter surrounding the stud axle 15 and projects exteriorly of the body 5 through one end wall thereof, the said axle 15 being of slightly greater length than the sleeve 18, so as to extend beyond the outer end thereof, and to the axle 15 and sleeve 18 are fixed oscillatory arms or levers 19, to the free

ends of which are pivoted throw links or rods 20, the latter being loosely connected to oppositely extending cranks 21 of a rotary shaft 22, the latter being journaled at 5 one end in a yoke bracket 23 fixed to one end wall of the body 5 and in a bearing plate 24 fixed to the said end wall in alignment with the yoke bracket. Thus, it will be seen that upon rotating the crank shaft 10 22, the rod or link connections 20 will cause reverse semi-rotary movement to be imparted to the stud axle 15 and sleeve 18, respectively, thereby oscillating the drum 9 and the rubbing head 16 connected with the 15 sleeve and stud axle, respectively, within the body 5 of the machine.

Fixed to one side of the body 5 is a yoke-like bearing bracket 24', the same being disposed at right angles to the bracket 23, and 20 has journaled therein a stud driving shaft 25, the latter having fixed thereto a bevel gear 26 meshing with a beveled gear 27 fixed to the crank shaft 22, so that upon rotation of the driving shaft 25, similar motion will 25 be imparted to the crank shaft, the driving shaft 25 being provided with the usual fly wheel 28 carrying a handle 29, whereby the fly wheel may be manually rotated as usual.

Arranged between the ends 11 of the drum 30 9 and the rubbing heads 16, and surrounding the stud shafts 14 and 15 are coiled compression springs 30 which permit the rubbing heads to retract on the packing of the clothes contained within the drum 9 during 35 the operation of the washing machine.

Mounted exteriorly upon the end wall of the body 5, directly above the stud axle 14 is a stationary arm 31, the same being formed with a depending lug 32, and likewise 40 the stud axle 14 is formed with an upwardly extending lug 33, the lugs 32 and 33 being engaged by a coiled spring 34 which tensions the said stud axle 14 when caused to partially rotate for limiting the rotation 45 of the head 16 of the said stud axle so that there will be no possibility of the clothes becoming torn or otherwise damaged should the same become packed within the drum.

It is, of course, understood that the oscillating arms 19 fixed to the stud axle 15

are suitably keyed thereto for longitudinal sliding movement thereon, thereby permitting the displacement of the stud axle 15 when the rubbing head 16 is being retracted within the drum 9 in the body 5 of the wash- 55 ing machine.

In the operation of the washing machine, the clothes are placed within the drum 9, it being understood that a sufficient quantity of water is introduced into the body 5, and 60 upon the rotation of the fly wheel 28, the drum 9 and one of the rubbing heads 16 are semi-rotated in reverse directions, thereby thoroughly agitating the water and the clothes for the cleansing thereof during the 65 operation of the washing machine.

What is claimed is:

A washing machine, comprising a stationary body, a semi-rotatable drum mounted therein, stud journals passed through the 70 ends of the body and the ends of the drum centrally thereof, a sleeve surrounding one stud journal and fixed to one end of the drum, the opposite end of the sleeve being projected exteriorly of the body, tensioning 75 means acting upon the other stud journal for sustaining the same under tension when partially rotated and also to limit its rotary movement, rubbing heads fixed to the inner ends of the stud journals, coiled expansion 80 springs interposed between the ends of the drum and the said rubbing heads, an arm fixed to the stud journal surrounded by the sleeve, an arm fixed to the sleeve, a double crank driven shaft mounted exteriorly of 85 the body, throw links loosely connected to the crank and to the said arms, respectively, and means co-operative with the driven shaft for rotating the same, whereby semi-rotary movements will be imparted to one of the 90 rubbing heads and the drum and cause the same to move in reverse directions to each other.

In testimony whereof I affix my signature in presence of two witnesses.

CHARLES WILLES.
